UNITED STATES PATENT OFFICE.

GEORGE E. TANT, OF NASHVILLE, TENNESSEE.

STOVE-LID LIFTER.

1,178,425.

Specification of Letters Patent.

Patented Apr. 4, 1916.

Application filed October 23, 1914. Serial No. 868,285.

To all whom it may concern:

Be it known that I, GEORGE E. TANT, a citizen of the United States, residing at Nashville, in the county of Davidson and State of Tennessee, have invented new and useful Improvements in Stove-Lid Lifters, of which the following is a specification.

The present invention contemplates the provision of a device, which while primarily intended for use as a stove lid lifter, is capable of lifting culinary utensils, cake pans and the like.

The invention aims to provide a device of this character comprising a pair of freely pivoted jaws associated with the handle in a manner to facilitate their association with the article to be lifted, and to effectively grip the same, thereby diminishing the liability of dropping the article, the device being so constructed that the heavier the article to be lifted the more effective is the gripping action of the jaws when the article is elevated.

In carrying out the invention it is my purpose to provide the upper jaw with a hook terminal for use in the capacity of opening oven doors as well as pulling pans and the like toward the door opening therefor, the hook being extended beyond the lower jaw to provide a guiding surface for automatically lifting the jaw to facilitate the association of the jaws with the lid, or the edge of the article to be lifted.

Among other features which will appear from the following description, the invention embodies simplicity in construction, durability and efficiency in its purpose.

In the drawing forming a part of this application, like numerals of reference indicate similar parts in the several views.

Figure 1 is a perspective view of the device. Fig. 2 is a vertical transverse sectional view. Fig. 3 is a view of the same applied to a stove lid. Fig. 4 is a view of the same used in connection with a pan.

Referring to the drawing in detail 5 designates the lower jaw of substantially rectangular formation in cross section, and having its free end curved upwardly as at 6. Fixed upon the jaw 5 is a U-shaped member 7 forming a bearing, between the parallel sides 8 of which is pivoted the shank 9 of the handle 10, the latter being constructed from any suitable material and of the desired shape.

Straddling the U-shaped member 7 at one

end thereof are the ears 11 formed on the upper jaw 12, a pin 13 being extended through the ears and parallel sides 8 of the U-shaped member and supporting said jaw 12 for relative pivotal movement with respect to the jaw 5. The jaw 12 is flat for a portion of its length, terminating at its forward end to provide the hook 14 for the purpose to be hereinafter described. The tail portion 15 of the jaw 12 overlies the U-shaped member 7, in which the free end of the shank 9 operates in the capacity of a cam for engagement with the tail portion 15 for moving the jaw to closed position. By reason of this construction, it will be manifest that the heavier the article to be lifted the more effective is the clamping action of the jaws.

The hook portion 14 extends beyond the free end of the jaw 5, thus providing a guiding surface 16 for automatically lifting the jaw 12 to permit both of the jaws to properly engage the article to be lifted. It is to be further noted, that by reason of the pivotal connection of the jaw 5 with the shank 7, and the fact that the jaw 12 is freely pivoted on the jaw 5, that both of the jaws normally assume an angular position with relation to the handle to facilitate the operative association with the lid, pan or other article to be elevated.

In addition to providing a guiding surface for automatically lifting or opening the jaws 12, the hook portion 14 thereof is intended for use in opening oven doors, and for withdrawing articles from within the oven toward the door opening therefor, thus eliminating all danger of burning the hands, as the result of the use of towels or clothes in the performance of this duty. Another important feature of the device resides in the fact that the same can be used without particular care on part of the user, and also that the hooked member 12 can be readily and easily hooked under the bails of pots, or other heavy articles to be lifted without the use of a cloth and without burning the hands.

It is believed that from the foregoing description, the nature and advantages of the invention will be readily apparent without requiring a more extended explanation, and therefore the same has been omitted. However I desire to have it understood that various changes in the construction, and arrange-

ment of parts may be resorted to when desired which fall within the scope of the appended claim.

What I claim is:—

5 As a new article of manufacture, a handle having a shank, a pair of spaced parallel plates pivotally mounted on the opposite sides of the shank adjacent one end thereof, a horizontally disposed base member carried by said plates and connected with the lower longitudinal edges of the latter, said base member projecting beyond the forward edge of said plates, a hook member having an extension overlying said end of the shank nor-

15 mally in spaced relation thereto and adapted to be acted upon thereby, intermediate spaced ears depending from said hook member, said ears straddling the plates and freely pivoted thereto whereby said hook normally assumes an angular position with relation to said handle, and the bill of said hook normally engaging the projecting portion of said base.

20 In testimony whereof I affix my signature in presence of two witnesses.

GEORGE E. TANT.
